United States Patent Office

Des. 182,866

Patented May 20, 1958

182,866

WRITING INSTRUMENT

Steven G. Yates, Lake Hiawatha, N. J., assignor to David Kahn, Inc., North Bergen Township, Hudson County, N. J., a corporation of New Jersey

Application May 29, 1953, Serial No. 25,240

Term of patent 14 years

(Cl. D74—17)

FIG. 1

FIG. 3

Fig. 1 is a side elevational view of a writing instrument as it appears with the point in retracted position;

Fig. 2 is a front elevational view; and

Fig. 3 is a top plan view thereof.

I claim:

The ornamental design for a writing instrument, substantially as shown.
